(57) **CLAIM**

The ornamental design for a car navigation device as shown and described.

DESCRIPTION

FIG. 1 is a front perspective view of a car navigation device. FIG. 2 is a rear perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right side elevation view thereof.

FIG. 8 is a left side elevation view thereof; and,

FIG. 9 is a perspective view thereof in an alternate position. The broken lines shown are included for the purpose of illustrating portions of the car navigation device that form no part of the claim.

1 Claim, 9 Drawing Sheets
